MATERNITY SUPPORT GARMENT

Minna R. Schubert, Saginaw, Mich., assignor to
 Le Monde Corset Company, Saginaw, Mich., a
 corporation of Michigan

Application January 4, 1943, Serial No. 471,311

7 Claims.

(Cl. 2—41)

This invention pertains to an improved maternity support garment and relates more particularly to a new and useful combination of shape-forming panels and supporting bands by which improved comfort, unhampered bodily movement and smooth fit are attained at all stages of the period of maternity.

An object is to provide a front panel capable of being adjusted to progressive changes in the shape and size of the wearer's figure so the same garment can be used throughout. To attain that object I provide means for adjusting at will the overall height of the front panel, shortening it while the form is flatter and lengthening during the later stages; such adjustments being made without bunching the material; permitting the front to adapt itself snugly and smoothly under all circumstances.

An object is to relieve the spine at the lumbar region of all forward and downward strain. I attain this object by providing, in combination with said front panel, a novel front girdling member that overlies the lower portion of the front panel and relieves the panel proper from having to support any appreciable part of the weight. The soft front panel therefore serves principally as a shape-controlling member. It also assists in keeping the other panels and principal members of the garment smooth and comfortable.

An object is to provide a simple and effective front girdling means adapted to support the groin region properly, that is, by a band that shall give greater stretch accommodation toward the lower groin where the greater part of the weight must be supported but where enlargement is less. I attain this desirable result by providing the supporting girdle at the front with means for adequate stretching along its upper marginal edge, there being progressively less yield in the parts nearer the bottom edge of such member.

A further object of my invention is to provide the back portion of the garment with a new and useful arrangement of members whereby pulls induced by supporting the weight at the front and other pulls developed by the wearer when bending from side to side, backward and forward, or when turning and twisting, are all distributed around and across the back of the body diagonally to the other side where they are, as it were, "anchored" at the opposite hip region. My arrangement of the back members attains the stress distribution just alluded to, yet allows the spine entire freedom for movement at and

above the waist line. Also, the tapered shape of the back members permits the use of unusually small lacings near the hips for adjusting the girth.

With the foregoing objects in view and certain others which will appear later in the specifications, my invention comprises the devices described and claimed and the equivalents thereof.

In the drawing, showing a preferred embodiment of my invention,

Fig. 1 is a plan view of the exterior of the garment as it appears when spread out flat;

Fig. 2 is a side view of the garment in use;

Fig. 3 is a front view; and

Fig. 4 shows a modified detail.

For better understanding this invention in use it may be regarded in a general way as somewhat resembling a sash that is drawn around the abdomen and up as far as the waist. The lower front margin of the sash supports the lower abdomen from beneath. The upper front part fits around the front of the abdomen and waist region, and gives correct shape without bulges, so that thin dresses worn over the sash would appear smooth and even. The pull produced in the sides of such a sash by the load at the front is transmitted around the waist and thence diagonally across the back of the body to the hip region at the opposite side.

Referring to Fig. 1, the garment as a whole comprises a front panel assembly indicated in general by the numeral 1, and a back part 2, the parts 1 and 2 being connected together by a narrow right-hand panel 3 permanently secured by a stayed seam 4.

The left-hand panel is a conventional "fastener" panel made in two parts, one part being secured to the left-hand edge of the front panel 1 by a reinforced stayed seam 5, the other part of the fastener panel being secured to the edge of the back part 2 by a soft seam 6. This left-hand fastener panel may be provided with hooks and eyes, as shown.

The front panel 1 consists of a piece of soft fabric 7 that covers the area between the seams 4 and 5 which may contain conventional flexible stays between the top hem 8 and the bottom hem 9. The panel fabric 7 has considerable fullness, being gathered as by pleating or Shirring along the right- and left-hand stayed seams 4 and 5 so the greatest fullness is at the middle portion of the panel to accommodate it to the body.

Upright casings 10, backed with tape and containing pull cords 11 are provided for the panel

1, in spaced arrangement as shown. The bottom ends of the pull cords are secured to the bottom of the panel at 12 and the cords allow the casing to slide on them when the panel is being gathered in or is being extended by sliding the top margin 8 up or down along the pull cords 11.

The take-up by means of the pull cords increases or decreases the overall height of the front panel, which is made shorter when the abdomen is flatter and is extended later in the maternity period of distention. This adjustment of length of the panel is availed of as the need increases, and by it the top hem of the garment can be kept at the desired height on the body under all conditions of use.

Numeral 13 designates a girdling member or band made of strong material, its ends being stitched at 14 to the seamed edges of the respective side panels. The bottom edge of member 13 is secured to the bottom hem 9 of the soft panel, but the upper hem 15 of member 13 is not sewn to the soft panel 7. The manner of attachment of member 13 to the soft panel 7 relieves the latter from the strain of carrying any of the body weight; that duty being performed solely by the girdling member 13.

A desirable feature of member 13 is that it is extensible near its top margin 15 to afford adequate accommodation for increased girth. The amount of extension permitted is less lower down toward the bottom hem 9. This extensible feature may be provided by an insert 16 of stretchable fabric preferably shaped as shown in Fig. 1, or by lacings, for adjustment without elasticity, as in Fig. 4. Spaced from the edges of the V-insert 16 are stays 16a which are downwardly and inwardly directed and stitched to girdling member 13. The stays 16a serve to keep the member 13 in shape, giving the desired amount of yielding stiffness to the elastic upper zone of member 13.

Panel 3 is a conventional side panel. It may have a flexible seam 4 in common with front panel 1, and is made of light non-stretchable fabric. Panel 3 extends from seam 4 to a double seam 17, which may be without stays. Intermediate the seams 6 and 17 is a double seam 18, the purpose of which will be explained later.

The back member consists of two parts, 19 and 21, alike in size and tapered. Member 19 has its greatest height at 17, and least at 6. Member 21 is the reverse. The left-hand small end of panel 19, Fig. 1, is anchored to the left-hand fastener panel at the seam 6. In member 19 adjacent seam 6 a lacer 20 is provided for girth adjusting. Member 19, being an extension of the side panel 3, its top margin has a hem which is a continuation of the top hem 8 on front fabric 7. The bottom edge of 19 is provided with a hem which is a continuation of bottom hem 9 of fabric 7.

The complementary panel 21 is secured at its large end to seam 6 and extends downwardly and to the right, Fig. 1, passing through a slit in panel 19 between the two adjacent seams 18, 19, being slidable therethrough to allow adjustments to be made by means of lacer 22. The small end of panel 21 is anchored to the seam 17.

It is thus seen that the garment may be adequately stayed according to the requirements of the user and of the wearer.

Having described the structure of the members of the garment in its preferred form, I will now explain their cooperative relation in use.

The garment is to be put on like a corset, being

fastened by the hooks and eyes in the left-hand fastener panel. Girth is then adjusted by means of the adjusters 20 at the wearer's left side and 22 at the right.

5 The bottom hem 9 of the front panel 7 is at the lower abdomen, Figs. 2 and 3, the upper hem 8 being adjusted to a desired waist height as indicated in Figs. 2 and 3. If the front shape is rather flat, then the front panel will be made 10 appropriately shorter by means of the pull strings 11. The take-in material is gathered down the front so it lies smooth, with only small gathers distributed the whole length and not bunched.

15 The front girdling member 13, being made of strong non-flexible material, supports the weight of the lower abdomen as indicated in Fig. 2. The lower hem 9 of member 13 does not stretch but the greater yield or adjustment near the top hem 15 gives that part of the abdomen a strong support. The endwise pull in member 13 is transmitted directly to the lower part of panel 3, thence to the lower part of the upright seam 6 at the hip. The action of part 21 is the same as for 19, but reversed. Consequently, the strong pull produced at the ends of girdle member 13 is thus transmitted principally from the lower parts of the side panels in two ways, namely, at the right to the small end of member 21 and the larger end of member 19. Likewise, the pull produced by the other end of girdling member 13 is transmitted in the reverse manner from seam 6 through the smaller end of member 19 and the larger end of 25 21. Girdling member 13 transmits the heavy pull around the waist and, via members 19 and 21, diagonally across the back of the wearer and to the hip area at the opposite side. When the body is bent from side to side, or twisted, or is bent forward or backward the two crossed and oppositely directed members 19, 21 take the resultant strains that are developed in the side panels. The two back members 19, 21, accommodate themselves to bodily movements by sliding slightly past each other.

30 The crossing point at the spine is the lowest part of the back panel, hence the spine region upward from the lower waist is entirely free.

This garment is made with or without garters, as is indicated in dotted lines. It is adapted to different figure types and exercises direct control of all parts that require support.

35 Changes of shape between 8 and 9, Fig. 2, increase progressively from the earliest to the final stages of use. At all stages the lower front or girdling portion of the garment serves as a lightly stayed shape-forming corset.

This garment fits smoothly at the sides, because of the under-arm side panels. The arrangement of overlying and crossing bands 19 and 21 at the back causes the back part to fit smoothly under all circumstances. Their overlapping arrangement makes the back doubly strong and firm.

40 The lacings, which ordinarily are a source of annoyance to the wearer of a maternity garment are here made unusually short and have the least possible amount of bulk. By the arrangement shown I am enabled to employ lacings of about one-fourth the length of the ordinary corset lacings, with all the adjustability that longer laces would have, yet I attain equal firmness and comfort, with less bulk and stiffness at the sides of the body. Persons with small figures prefer garments with the least possible amount of lacing and with a minimum of stiffness.

It is now apparent that I have provided a maternity garment having a novel action which I have alluded to as somewhat sash-like, whereby the spine is relieved of strain and all pull is distributed comfortably over an extensive area of the wearer's back below the waist line; also, that the lower front abdominal region is held up firmly but with an appropriate degree of yield or adjustability along its upper marginal edge, for the greater comfort of the user.

Having thus described my invention, what I claim and desire to secure by Letters Patent is:

1. A maternity garment having side panels and a body portion comprising a front panel of soft fabric formed with gathers along its side marginal hems and having intermediate upright pull cords adapted to change at will the height of said soft panel; a girdling support member overlying the lower region of said front panel, its side and bottom edges being secured to the marginal side and bottom hems of the panel, its upper marginal edge being free; a V-shaped extensible means inserted in the girdling member at mid length thereof, being adapted for greatest extension near its top margin and less toward the bottom; the back portion of said garment comprising two bands tapered lengthwise and extending across the wearer's back in overlapped arrangement from one side diagonally downward to the opposite side at the hip region, the narrow end of one of said bands and the wide end of the other being secured to an upright seam of a side panel of the garment at the said hip bone region, girth adjusting means in the narrow end portion of each band; one of said bands being formed with a slit near its wide end slidably receiving the narrow end portion of the other band, thereby permitting movements of said overlapping bands relatively to each other in their lengthwise direction.

2. A maternity garment having side panels and a body portion comprising a front panel formed with gathers along its side edges and having pull cords adapted to adjust the height of said panel; a girdling support member overlying the lower region of said front panel, its side and bottom edges being secured to the front panel, its upper edge being free; a V-shaped insert of elastic material intermediate the ends of said girdling member and capable of maximum stretch along the upper edge of such member and progressively less toward its lower edge; the back portion of said garment comprising two bands extending across the wearer's back in overlapped arrangement from one side diagonally downward to the opposite side, a narrow part of one of said bands and a wide end portion of the other being secured together and to an upright seam of a side panel of the garment; girth adjusting means in the narrow end portion of each band; one of said bands being formed with a slit near its wide end, the narrow end portion of the other band slidably received therein.

3. A maternity garment body portion comprising a front panel of soft fabric having means for varying the overall height thereof; in combination with a girdling member overlying the lower portion of said front panel and girdling the same, said member being secured along its bottom edge to the bottom edge of the front panel in non-stretchable relation thereto; the side edges being secured to the side edges of the front panel, its upper edge being unattached to the front panel, and including a stretchable member inserted therein.

4. A maternity garment body portion comprising a front panel of soft fabric having adjustable means for varying the overall height thereof; a support member overlying and girdling the lower portion of said soft panel, being secured thereto along the contiguous side and bottom edges, the upper edge of said support member being free; and means for increasing the girth of said girdling member along its upper marginal portion.

5. A maternity garment comprising a body portion consisting of a front panel of soft fabric having means for varying the overall height thereof; a support member overlying the lower portion of said front panel and girdling the same, being secured thereto along its side and bottom edges only; and means for varying the length of the upper marginal part of said girdling member, said means comprising an elastic insert in the middle upper portion of said member.

6. A maternity garment comprising a body portion consisting of a front panel of soft fabric having means for varying the overall height thereof, and a support member overlying and girdling the lower portion of said front panel, being secured thereto along its side and bottom edges only, its upper edge being free; and a back member of said garment comprising two overlying tapered bands extending from each side diagonally downward to the opposite side, each band being narrower at one end, the narrow end of each band being secured to a part of the garment at the hip bone region.

7. A maternity garment comprising a body portion consisting of a front panel of soft fabric having means for varying the overall height thereof; a support member overlying and girdling the lower portion of said front panel, being secured thereto along its side and bottom edges only, its upper edge being free, a back member of said garment comprising two overlying tapered bands extending from each side diagonally downward to the opposite side, the narrower end of each band being secured to a part of the garment over the hip bone region; and length adjusting means in the narrower portion of each band; one of said bands being formed with a slit slidably receiving the narrow portion of the complementary band.
